UNITED STATES PATENT OFFICE.

HENRI TENTING, OF PARIS, FRANCE.

VALVE APPARATUS FOR STEAM ENGINES AND PUMPS.

SPECIFICATION forming part of Letters Patent No. 309,418, dated December 16, 1884.

Application filed June 4, 1884. (No model.)

To all whom it may concern:

Be it known that I, HENRI TENTING, a citizen of France, residing at Paris, in the department of the Seine, have invented new and useful Improvements in Valve Apparatus for Steam-Engines, Pumps, and the like, of which the following is a specification.

This invention relates more particularly to steam-engines, pumps for water and gas, and to like machines which have steam or fluid passages in the piston, and in which the latter is given an axial movement of vibration in addition to the ordinary reciprocation, such axial movement operating to change the ports so as to admit the fluid alternately to opposite ends of the cylinder.

The invention consists in placing the valve-ports outside the cylinder instead of having them inside, as heretofore. The rubbing-surfaces of the piston and cylinder thus are or may be unbroken, and the valve-seat is more accessible.

It also consists in certain special constructions, combinations, and arrangements of parts, as hereinafter set forth.

The accompanying drawings represent a steam-engine embodying the invention in what is considered the best form.

Figure 1 is a plan; Fig. 2, an end elevation; Fig. 3, a front elevation, partly in section; Fig. 4, a vertical cross-section on line *x y*, Fig. 3, and Fig. 5 a detail view.

The cylinder *P* is in the two ends of the frame, and the valve apparatus and crank mechanism are in the chamber in the middle. The piston-heads *D* are connected together at the back (see Fig. 4) by a segmental connection, *m n*, so that the two heads move and turn together. This connection is slotted, and in the slot is the cam *K*, which is fixed on the cross-shaft *J*. As the shaft revolves the cam, acting on the surfaces *m* and *n*, turn the piston first in one direction and then in the other. In the piston-heads and the lower part, *n*, of the segmental connection are the steam-passages *C C'*, which open at one end into the steam-spaces *V V'*, respectively, and at the opposite end are closed. The valve-ports *c' c*, of oblong form, are in the side of the steam-passages. *A* is the inlet-port; *B' B*, exhaust-ports of the valve-seat. The port *A* is at the

end of the steam-passage *S*, the ports *B B'* of the passage *T*. In front of the segmental piston-connection is the plate *F*, which abuts at the ends against the inner face of the piston-heads, but does not turn with them. This plate, therefore, partakes of the usual reciprocatory movement of the piston in a right line, but is not vibrated. At the middle it is slotted, the shaft *J* passing through the slot *O*. It is provided in the front face with ways *G*, in which moves the slide *H*. The ways are partly above and partly below the slot. The slide is connected, by the wrist-pin *i*, with crank-pin *I* fixed on the shaft *J*. It is of such length that when the crank is vertical or nearly vertical it is wholly on one side of the slot. It is therefore carried by the revolution of the wrist-pin first over, then under, the shaft. In this way the necessity of dividing the shaft is avoided. The segmental connection or valve *m n* is held to its seat by the springs *r r'*. These are flat leaf-springs, (see Fig. 5,) which at the ends are held in sockets of the plate *F*, and at the middle bear upon the conical ends *w w'* of the screws *W* and *W'*, tapped into the piston-heads at the axis thereof. By turning these screws the points compress the springs and cause them to press the piston toward the side of the valve-seat with greater pressure. Being axial, the screws do not interfere with the vibratory movement of the piston.

The operation is as follows: Steam enters by the passages *S* in the engine-frame, and passes by way of the ports *A c* and steam-passage *C* into the space *V* at the right end of the cylinder, between the piston and the cylinder-head *Q*, and forces the piston to the left in the direction of the arrow *U*. The plate *F* and slide *H* are carried with the piston and turn the crank *I* and shaft *J* to the left in the direction of the arrow *Z*. In its revolution the shaft *J* has, through the cam *K*, turned the piston to the left, as indicated by the arrow, Fig. 4, thereby putting the steam-passages *S C* into communication through the steam-ports *A c*. The exhaust-steam from the space *V'*, between the piston and the cylinder-head *Q'*, escapes through the passage *C'*, ports *c' B'*, and exhaust-passage *T*. By the continued revolution the cam *K*, acting upon the surface of the

port *m*, turns the piston to the right, (opposite to arrow, Fig. 4,) so as to cut off the steam, and then, continuing to turn it to the right, brings the port *c'* opposite the port *A*, and lets 5 the steam into the space *V'*, so as to impel the piston in the opposite direction.

It may be remarked that the usual accessories of a steam-engine—such as the regulator, fly-wheel, &c.—may be used; also that the 10 invention is equally applicable to various kinds of engines, whether with one or with several cylinders, or to compound engines, for example.

In applying the invention to water-pumps, 15 the shaft *J* being driven from a suitable motor, the passage *S* is the inlet and *T* the outlet, and the ordinary appliances of check-valves and the like may be used.

It is evident that modifications may be made 20 in the details of construction without departing from the spirit of the invention, and that parts of the invention may be used separately. Thus the forms, dimensions, proportions, and materials, as well as the arrangement of parts 25 may be changed, and the movements may be transmitted from or to the piston by devices of various kinds.

Having now fully described my said invention and the manner of carrying the same into 30 effect, what I claim is—

1. The reciprocatory and vibratory piston, provided with passages and ports, in combination with the cylinder and the valve-seat, and its ports arranged outside said cylinder, 35 substantially as described.

2. The combination, with the cylinder, formed in the two ends of the machine-frame, of the reciprocatory and vibratory piston, composed of the piston-heads and segmental

connection, and provided with passages and 40 ports, and the valve-seat opposite the segmental connection, substantially as described.

3. The combination, with the cylinder, the 45 piston provided with passages and ports, and the valve-seat, of the cross-shaft, the crank-connection between the shaft and piston, and the cam mounted on said shaft for vibrating said piston, substantially as described.

4. The combination, with the cylinder and piston, having a transverse slot in the middle, 50 the shaft passing through said slot, the connections between the shaft and piston, and the valve apparatus for admitting the fluid alternately into spaces between the piston and cylinder-heads on opposite sides of the slotted 55 portion, substantially as described.

5. The combination of the slotted plate, the shaft passing through the slot, the ways on each side of said slot, the slide moving in said ways and crossing from one side to the other 60 of said slot, the crank on the shaft, and the wrist-pin connecting the crank with the slide, substantially as described.

6. The combination of the cylinder, piston, 65 valve formed by said piston, cross-shaft, slotted plate provided with ways, slide moving in said ways, crank and wrist-pin connected with said slide, and cam for imparting an axial movement of vibration to said piston, substantially as described.

In testimony whereof I have hereunto set my hand in the presence of two subscribing witnesses.

HENRI TENTING.
